UNITED STATES PATENT OFFICE

SAMUEL B. BOWMAN, OF ZANESVILLE, OHIO, ASSIGNOR TO HAZEL-ATLAS GLASS CO., OF WHEELING, WEST VIRGINIA, A CORPORATION OF WEST VIRGINIA

LEER

Application filed September 14, 1929. Serial No. 392,608.

The present invention is an improvement on the leer disclosed in my pending application Serial No. 286,125, filed June 18, 1928.

One of the material objects of the present invention is to reduce the fuel consumption in the operation of leers. The loss of heat in the operation of leers is due to some extent to the direct conduction of heat by metal parts extending from the interior or heated 10 part of a leer to the exterior thereof. One of the objects of the present invention is to eliminate this source of heat loss by a construction in which there are no metal connections between the interior and the exterior 15 of the leer.

The invention also involves various other features for conserving the heat of the leer, and other improvements which will be apparent to those skilled in the art, from the 20 following description. In view of the fact that the present invention constitutes an improvement in the leer construction shown in my application #286,125, the leer as a whole will be described somewhat generally, and 25 the particular improvements involved herein will be described in more detail.

Referring to the drawings:

Figure 1 is a perspective view of the improved leer, parts being broken away to 30 show the interior construction; and

Figure 2 is a vertical transverse sectional view taken on the line 2-2 of Figure 1.

In general, the leer includes an ordinary 35 endless chain conveyer 1, which extends the entire length of the leer. Arranged beneath the forward end of the endless conveyer is the fire-box 2; and the furnace, which 40 encloses the endless conveyer for a substantial portion of its length, is referred to generally by numeral 3. At intervals the furnace is provided, as in the usual practice, with curtains or baffles 4, which are vertically 45 adjusted by any desired means, such as by holes 5 and pin 6. I also preferably employ a plurality of hood members 7, which are 50 arranged over the endless conveyer, rearwardly of the furnace; the hood members are removable, and of course, the number of members employed depends upon the particular conditions.

Referring now to the particular construction of the furnace, numeral 8 indicates angle irons which extend the entire length of the leer, and which carry the leer bottom plate 9 which extends substantially the full 55 length and width of the leer, and is preferably formed of a plurality of plates riveted together.

At suitable intervals throughout the length of the furnace, are oppositely arranged foot 60 members 10 which are inclined upwardly and inwardly, and which have their inner ends riveted to transversely extending angle irons 11. Thus the transverse angle irons are spaced above the bottom plate 9, and the 65 ends of the angle irons are spaced inwardly from the sides of the furnace. The foot members 10 are supported by the angle irons 8, but it is to be particularly noted that they are insulated from the angle irons by blocks of 70 heat insulating material 12, such as transite. Also to reduce the conduction of heat the foot members are preferably provided with one or more holes 13.

Mounted on top of each of the transverse 75 angle irons 11, is a strip of heat insulating material 14, such as transite, and resting thereon are two channel irons 15, properly spaced, and extending the full length of the furnace; the flanges of the channel irons projecting inwardly. These channel irons 80 perform various functions. For example, they partially form the side walls of the leer tunnel, and also partially support both the upper and lower runs of the endless conveyer. The 85 channel irons are maintained in proper spaced relation by means of spacers or tie rods 16, which are preferably in the form of channel irons or angle irons.

The leer pans forming the endless conveyer 90 are hingedly connected, as indicated by numeral 17, and it will be noted that the ends of these leer pans, while traveling in the lower run of the conveyer, rest on the lower flanges of the channel irons 15. For the purpose of 95 supporting the intermediate portions of the leer pans, while in the lower run of the conveyer, I provide two rails 18, which are supported by the angle iron 11, but which are insulated therefrom by the strip of transite 100

14. In the upper run of the conveyer, the ends of the leer pans ride on the upper flanges of the channel irons 15. And for the purpose of supporting the intermediate portions 5 of the leer pans while in the upper run of the conveyer, I provide a T beam 19 which is supported by and riveted to the tie beams 16.

As stated above, the channel irons 15 partially form the side walls of the tunnel. To 10 complete the side walls of the tunnel I employ two longitudinally extending vertical slabs or sheets of heat insulating material 20, preferably transite. These slabs or sheets are mounted on the upper flanges of the channel 15 irons 15, and are secured in place by angle irons 21. It will be noted that the walls 20 of heat insulating material are arranged on the outer portion of the channel iron flanges, leaving the inner portion of the flanges as 20 rails for the leer pans of the upper run of the conveyer.

To complete the tunnel, the roof is also formed of slabs or sheets of heat insulating material 22, preferably transite, which rest 25 on the side walls 20; the side walls and roof being secured together by short sections of angle irons 23.

The space between the bottom 9 of the furnace and the tops of the transverse angle 30 irons 11, is packed with heat insulating material 24, such as sil-o-cel. Of course, this packing of sil-o-cel extends the entire width of the leer to the angle irons 8. This completes the bottom of the leer up to the level 35 of the tops of the transverse angle irons 11. Surrounding the side walls and top of the tunnel are blocks of heat insulating material 25, such as sil-o-cel. And the insulation is completed by a second layer of blocks 26, 40 also preferably of sil-o-cel, which entirely houses the first jacket of sil-o-cel blocks.

For the purpose of protecting the blocks of insulating material, I preferably arrange metal sheets 27 along the sides of the leer, and 45 similar sheets 28 on the top thereof, with angle irons 29 extending along the upper edges. This metallic casing, if employed, is secured in place by a plurality of straps 30 having their lower ends secured to the angle 50 irons 8 and their upper ends bent over the angle irons 29; oppositely arranged straps being adjustably connected at their upper ends by the threaded tie rods 31.

A plate 32 is attached to the front of the 55 leer, and slidably mounted on said plate is a door 33 which is made of heat insulating material. The door is provided with racks 34 engaged by gears 35 fixed to a shaft 36 which is rotatably mounted in bearings 37; 60 a hand wheel 38 being provided for the purpose of rotating the shaft. Thus the door may be vertically adjusted according to the height of the ware being annealed, thereby further conserving the heat of the leer. For 65 the purpose of maintaining the door in its

vertically adjusted position, I provide a pawl 39 which engages a ratchet wheel 40 fixed to the shaft 36.

From the foregoing description it will be apparent that while the leer is unusually simple in construction, and relatively inexpensive in manufacture, yet it is one which is highly efficient in operation and most economical in fuel consumption. It will also be noted that in the construction described, there is no direct conduction of heat by metal from the interior of the leer to the exterior thereof. 70 75

While the invention has been described in considerable detail, it will be understood that it is subject to numerous modifications and changes, all of which I aim to include in the scope of the appended claims. 80

Having fully described my invention, what I claim as new is:

1. A leer including channel irons partly forming the side walls of the tunnel, heat insulating blocks mounted on said channel irons and completing the tunnel side walls, a roof of heat insulating material mounted on said blocks, and an endless conveyer traveling through the tunnel. 85 90

2. A leer including metallic members partly forming the side walls of the tunnel, heat insulating blocks mounted on said metallic members and completing the tunnel side walls, an endless conveyer traveling through the tunnel, and flanges on the metallic members supporting the upper run of the conveyer. 95

3. A leer including parallel spaced channel irons partly forming the side walls of the tunnel, an endless conveyer traveling through the tunnel, the upper flanges of the channel irons forming supports for the upper run of the conveyer, and the lower flanges of the channel irons forming supports for the lower run of the conveyer. 100 105

4. A leer including parallel spaced channel irons partly forming the side walls of the tunnel, an endless conveyer traveling through the tunnel, the upper flanges of the channel irons forming supports for the upper run of the conveyer, the lower flanges of the channel irons forming supports for the lower run of the conveyer, and blocks of heat insulating material mounted on the upper flanges to complete the tunnel side walls. 110 115

5. A leer including longitudinally extending frames, transverse members spaced from the bottom and sides of the leer, a tunnel supported by said transverse members, foot members attached to said transverse members and supported by said frames, and heat insulation material between the foot members and the frames. 120 125

6. A leer including a plurality of transverse members spaced from the bottom and sides of the leer, two parallel longitudinally extending channel irons supported by said transverse members and partly forming the 130

side walls of the tunnel, an endless conveyer traveling between the channel irons, and blocks of heat insulating material jacketing said channel irons.

5 7. A leer including a plurality of transverse members spaced from the bottom and sides of the leer, two parallel longitudinally extending metallic members supported by said transverse members and partly forming 10 the side walls of the tunnel, heat insulating material completing the walls of the tunnel, and heat insulating material filling the space between the tunnel and the top, bottom, and sides of the leer.

15 8. A leer including a plurality of transverse members spaced from the bottom and sides of the leer, rails mounted on said members but insulated therefrom, tunnel side walls mounted on said members but insulated 20 therefrom, and an endless conveyer, the lower run of said conveyer adapted to ride on said rails.

9. A leer including a plurality of transverse members spaced from the bottom and 25 sides of the leer, tunnel side walls mounted on said members but insulated therefrom, tie rods connecting the side walls, a longitudinally extending **T** beam mounted on said tie rods, and an endless conveyer, the upper run 30 of said conveyer adapted to ride on the **T** beam.

10. A leer including a tunnel, a leer frame, a conveyer adapted to carry ware through the tunnel, the upper and lower runs of said conveyer being within the tunnel, the top, bottom and sides of the tunnel being spaced from the top, bottom and sides respectively of the leer, heat insulating material filling the space between the tops, bottoms and sides of the 40 tunnel and leer, downwardly extending metal parts for supporting the tunnel thus spaced from the top, bottom and sides of the leer, and means for insulating the metal parts from the leer frame.
